COUNTER FOR TOILET SEAT GUARD
DISPENSERS

Charles D. Morton, River Forest, Ill.

Application January 15, 1934, Serial No. 706,601

5 Claims.

(Cl. 194—1)

The present invention relates to an improved type of coin controlled toilet seat cover or guard dispenser and more particularly to a dispenser having improved counting means for keeping track of the covers or guards as they are dispensed from the machine and furthermore serving as a means for automatically locking the coin receiving mechanism to prevent the insertion of coins into the machine when the same is empty.

It is an object of this invention to provide a toilet seat cover or guard dispenser with control means for locking the machine when empty.

It is also an object of this invention to provide an improved type of toilet seat guard dispenser having a counting mechanism including means for automatically locking the coin receiving slot when the last toilet seat guard is discharged from the dispenser.

It is a further object of this invention to provide an improved type of toilet seat guard dispenser wherein the dispensing mechanism of the machine is adapted to be locked against operation by a counting mechanism which registers the guards as they are dispensed and automatically holds a control member in a locked position whereby the coin receiving slot of the machine is closed to prevent the insertion of coins into the machine when the same is empty.

It is furthermore an object of this invention to provide an improved toilet seat guard dispenser with an adjustable support whereby the dispenser housing may be raised or lowered or moved backwardly or forwardly on a toilet bowl on which the dispenser is mounted.

It is an important object of this invention to provide an improved type of toilet seat guard dispenser adapted to be conveniently mounted on a toilet bowl by means of an adjustable bracket, said dispenser enclosing a pad of folded and connected toilet seat covers or guards adapted to be dispensed one at a time by the operation of a coin controlled mechanism which registers the covers or guards as they are dispensed and furthermore automatically causes locking of a control mechanism when the last guard is dispensed so that the coin receiving slot of the dispenser is locked thereby preventing the insertion of coins into the dispenser when the same is empty.

Other and further important objects of this invention will be apparent from the disclosures in the specification and the accompanying drawings.

The invention (in a preferred form) is illus-

trated in the drawings and hereinafter more fully described.

On the drawings:

Figure 1 is a side elevation of a toilet seat guard dispenser embodying the principles of this invention and illustrated mounted in position on a toilet bowl by means of the toilet seat hinge posts.

Figure 2 is an enlarged fragmentary rear view of the dispenser illustrating the adjustable dispenser supporting bracket.

Figure 3 is an enlarged vertical detail section taken on line III—III of Figure 2.

Figure 4 is a plan view of the lower half of the back plate of the front section of the dispenser.

Figure 5 is an enlarged front elevational view of the front section of the dispenser taken on line V—V of Figure 1.

Figure 6 illustrates a fragmentary portion of the interior mechanism of the front section of the dispenser with the guard dispensing mechanism omitted and illustrating the counting mechanism showing the locked position of the control lever in dotted lines.

Figure 7 is a fragmentary vertical detail section taken on line VII—VII of Figure 6 and illustrating the spring controlled latching pin in its outermost or released position.

Figure 8 is a detail fragmentary section similar to that illustrated in Figure 7, showing the spring-controlled latching pin in its closed or locking position.

As shown on the drawings:

As illustrated in Figure 1, the reference numeral 1 indicates a toilet bowl, the upper rear portion of which is equipped with a pair of hinge bolts or posts 2 on which a toilet seat 3 is hingedly connected.

The improved toilet seat guard dispenser is adapted to be mounted in position on the upper rear portion of the toilet bowl 1 by means of a pair of adjustable supporting brackets. Each set of brackets comprises a foot plate 4 having a pair of parallel slots 5 therein to permit the threaded bolt ends of the hinge posts to be projected therethrough. The plurality of slots 5 permit the dispenser to be mounted at different distances from the rear end of the toilet bowl.

Integrally formed on the rear margin of the foot plate 4 and projecting upwardly therefrom is a channel cross-sectioned guide member or leg section 6. The lower leg section 6 is provided with an aperture through which a clamping bolt 7 projects. Forming part of each of the brackets is an upper leg section 8 having a longitudinal slot

9 opening through the lower end thereof to permit the upper leg section to be slidably engaged on the clamping bolt 7 to hold the leg sections 6 and 8 clamped together in an adjusted position. 5 The upper leg section 8 is offset at 10 and has the upper end thereof bent at an angle to form a mounting arm 11 which is rigidly secured to the back wall of the rear section or magazine 12 forming part of the dispenser. The adjustment 10 between the leg sections 6 and 8 permits the dispenser to be raised or lowered with respect to the top of the toilet bowl. The magazine 12 is arranged to hold a pad of one hundred toilet seat covers or guards which are adapted to be 15 dispensed one at a time from the machine against a guide or deflecting shield 13 which is integrally formed on the lower margin of the back plate of the magazine 12 as clearly illustrated in Figures 1 and 2. 20 The toilet seat covers or guards are adapted to be discharged from the machine by means of a coin-controlled dispensing mechanism mounted within a front casing or housing 14 which, when in its closed position as illustrated in Fig. 1, fits over the back section or magazine 12. The toilet seat cover or guard dispensing mechanisms are similar to those illustrated and described in my copending application for patent for a "Toilet seat guard dispenser", filed July 15, 1932, U. S. Serial No. 30 622,685. The toilet seat covers or guards are of the type disclosed in the application hereinbefore referred to and are of oval shape or of a shape complementary to the shape of the toilet seats and have the middle portions thereof cut to provide 35 a flap or apron leaving an opening in the middle portion of the guard. The front casing or housing 14 has the lower end thereof pivotally connected to the side flanges of the magazine 12. Secured within the rear portion of the casing or housing 14 is a partition or 40 rear plate 15 to divide the interior of the casing into a closed dispensing mechanism chamber and a rear open compartment or chamber adapted to fit over the magazine 12 to enclose the pad or stack of toilet seat guards. The front or main 45 casing of the dispenser is adapted to be locked to the magazine by means of a key-operated lock as illustrated and described in my earlier application. By unlocking the main casing the same 50 may be swung downwardly into an open position to permit a new pad of seat covers or guards to be mounted in position within the rear section or magazine. 55 The guard dispenser is adapted to be controlled by the depositing of a coin in a coin receiving slot 16 (Figure 6) provided in the top wall of the dispenser housing 14. The coin slot 16 continues 60 downwardly through the top wall of a coin guide chute 17 mounted within the upper portion of the dispenser housing. A deposited coin is permitted to drop downwardly through the slot 16 into a guide slot 18 provided in the chute 17. A coin discharge opening or slot 19 is provided near one 65 end of the discharge chute to permit a deposited coin to be discharged downwardly out of the coin chute into a coin receiving box 20 mounted in position to close an opening provided in one side of the closure plate 15. 70 Projecting through a slot in the top of the housing 14 is a finger piece 21 the lower or inner end of which has a bar or arm 22 projecting from one side thereof. A coin actuating stud or pusher finger 23 is secured to project at right angles from one side of the pusher arm 22 and extends through 75 longitudinal slots 24 provided in the side plates

forming parts of the coin chute 17. One end of one of the slots 24 is open and communicates with an enlarged slot 25 provided in one of the side plates of the coin chute 17.

Pivotedly mounted on one side of the coin chute 5 17 is a spring controlled pawl 26. A control roller 27 is supported on the pawl 26 and is positioned to coat with a cam edge forming a part of the inner end of the finger piece 21. The cam shaped end of the finger piece 21 coating with the roller 10 27 acts to hold the pawl 26 in its released position.

Slidably engaged in the upper portion of the housing 14 adjacent the inner surface of the plate 15 is an actuating bar 28 provided with a latching notch 29 in the lower edge thereof. One end of 15 the operating bar 28 is provided with a pair of spaced teeth or projections 30 projecting at right angles from the bar and extending through the slot 25 into the coin guide groove or passage 18 as clearly illustrated in Figure 6. The two teeth 30 20 are adapted to serve as stops against which a coin 31 is adapted to be engaged when the control pin or stud 23 operated by the finger piece 21 is projected against one edge of the deposited coin to permit actuation of the seat cover guard dispensing mechanism. The two coin slot teeth 30 are spaced apart to permit the coin pushing pin or stud 23 to pass between the teeth 30 when no coin is deposited, thereby providing an arrangement permitting the finger piece 21 to be actuated 30 without causing operation of the operating bar 28 and the seat cover guard dispensing mechanism operable thereby. When a coin is deposited it drops into a position between the stud 23 and the teeth 30 so that when the finger piece 21 is 35 moved from the position illustrated in Figure 5 the cam edge thereof is moved out of engagement with the roller 27, thereby permitting the spring controlled pawl 26 to swing upwardly into the latching notch 29 (Figure 6) when said notch 40 is brought into register with the toothed end of the pawl 26 by the slidable movement of the operating bar 28 which is accomplished through the medium of the deposited coin. The operating bar 28 is thus held in a locked or latched position 45 until the finger piece 21 is released and is returned into its normal position by the action of a control spring 32 having one end thereof connected with the finger piece while the other end is connected to one of the side walls of the housing 14. 50 With the return of the finger piece 21 to its normal position the latching pawl 26 is moved into a released position by the cam edge of the finger piece, thereby causing release of the operating bar 28. 55

Pivotedly connected to one end of the operating bar 28 is one end of a link or connecting bar 33. The lower end of the connecting bar 33 is pivotally connected to a slidable or vertically reciprocating frame or carriage 34. A coiled control spring 60 35 is connected to the connecting bar 33 and to the carriage 34 as illustrated in Figure 5. Pivotedly connected to cross members of the carriage 34 are the upper ends of a plurality of hinge members 36, the lower ends of which are hingedly 65 connected to a pair of seat cover guard dispensing shoes 37, each of which is provided with a sponge rubber dispensing cushion or pad 38. The partition plate 15 is provided with elongated slots or openings 39 through which the dispensing pads are adapted to be projected into the rear compartment or magazine of the dispenser into frictional contact with a portion of a folded toilet seat cover or guard, a pad or stack of which is 70 75

supported within the magazine 12 of the dispenser. The dispensing pads 37 normally drop by gravity back through the openings 39 into the front compartment of the dispenser housing as illustrated in Figure 4. The slideable carriage 34 is normally held in its uppermost position by means of a coiled control spring 40 connected to the carriage and to a stationary support within the housing 14. The dispensing pads 37 are adapted to be projected through the opening 39 into engagement with one of the folded toilet seat guards within the magazine 12 each time the control finger piece 21 is actuated regardless of whether a coin has been deposited in the dispenser or not. No dispensing of a toilet seat guard from the dispenser casing is accomplished until the slideable carriage 34 is moved downwardly from the full line position of Figure 5 with the pads projected into engagement with one of the guards in the magazine. This can only be accomplished by the depositing of a coin and the subsequent operation of the finger piece 21. The pads 37 are projected into engagement with a toilet seat guard by a finger piece control mechanism comprising a coiled spring 41 connected to the finger piece 21 and to one side of an arm 42. The arm 42 is secured to one side of the upper end of a guide lever 43. The lower end of the lever 43 is pivotally secured to one side of the lower portion of the partition plate 15. A slot 44 is provided longitudinally in the lever 43 for the reception of a roller rotatably supported on one side of an arm 45 the lower end of which is pivotally supported on the carriage 34. Secured to the arm 45 is one end of an arm 46 having the outer end thereof pivotally connected to a bell crank 47 which is pivotally supported on one of the upper corners of the carriage 34. The bell crank member 47 is provided with an opening in one of the arms thereof through which a ball member 48 projects. The ball member 48 is connected to one of the cross rods 65 of the carriage to which the hinge members 36 are connected. When the bell crank 47 is actuated, the upper cross rod is rocked or partially rotated to actuate the hinge members 36 to thereby swing the same from their normal lowered position upwardly and out through the plate openings 39 into frictional gripping contact with the foremost folded toilet seat guard in the magazine 12. For the purpose of locking the coin receiving mechanism so that coins cannot be deposited in the dispenser when the same is empty, a counting or registering mechanism is provided in the dispenser and is operable each time a toilet seat guard is discharged from the machine, so that when the last guard is dispensed a locking member will be automatically moved into position beneath the coin receiving slot 16 to prevent the insertion of coins into an empty dispenser. Rotatably mounted on the partition plate 15 is a ratchet wheel 49 provided with 100 teeth to correspond with the number of toilet seat covers or guards usually provided in each pad of guards mounted in the dispenser magazine 12. The side of the ratchet wheel 49 which is disposed adjacent the partition plate 15 is provided with a circular graduated scale 50, in the present instance divided into increments of 5, as clearly illustrated in Figure 4. Each time a guard is dispensed from the machine the ratchet wheel 49 is rotated 1/100th of a revolution by means of an operating ratchet or pawl 51. The circular scale

50 is observable through a sight opening 52 provided in the partition plate 15. Also coacting with the teeth of the ratchet wheel 49 is a stop ratchet or pawl 53 which is pivotally supported on the plate 15 and is controlled by means of a spring 54. The operating pawl 51 is spring-controlled and is pivotally mounted on one side of a counter actuating lever or bar 55 which is pivotally supported on the stub shaft on which the ratchet wheel 49 is mounted. Pivotally supported on the upper end of the counter control lever 55 is a coin opening closure bar or bolt 56 having a longitudinally disposed slot or notch 57 provided in one end thereof to permit the latching bolt to slide over the coin actuating pin 15 or stud 23. As clearly illustrated in Figure 6, the closure bolt 56 has the notched end thereof slidably projected into the coin receiving slot 16 and when in closing position as illustrated in dotted lines in Figure 6, is positioned beneath the coin receiving slot 16 to prevent the insertion of a coin into the dispenser. When the closure bolt 56 is in a closing position as shown in dotted lines in Figure 6, the operating lever 55 is locked in the dotted line position illustrated in Figure 6 by means of a latching pin 58 which is supported on one end of a strap spring 59 mounted on one side of the control lever 55 beneath the pivotal support thereof. The latching pin 58 projects through an opening in the lever 55 into frictional contact with one surface of the ratchet wheel 49 which serves to hold the latching pin 58 in its released position as illustrated in Figure 7. The ratchet wheel 49 is provided with an aperture 60 which, with the operation of the ratchet 35 wheel 49, is adapted to be gradually advanced toward the latching pin 58 until the last toilet seat cover or guard is discharged from the dispenser when the aperture 60 is brought into register with the pin receiving opening of the control lever 55 thereby permitting the spring 49 to automatically project the latching pin 58 into the aperture 60 as illustrated in Figure 8. When the latching pin 58 is moved out of the aperture 60 the control lever 55 is moved from the dotted line position of Figure 6 into the full line position by means of a coiled control spring 61 which is connected to the lower end of the lever and to a pin or post secured on the lower portion of the partition plate 15 as clearly illustrated in Figure 6. For the purpose of limiting the pivotal swing of the control lever 55, said lever is provided with a pin or stud 62 which projects into an aperture or opening 63 provided in the partition plate 15 as clearly illustrated in Figure 4. The stop pin 62 is of less diameter than the diameter of the opening 63 so that the pin may be swung from one side to the other of said opening to limit the pivotal swing of the lever. When the latching pin 58 is engaged in the aperture 60 of the ratchet wheel 49, the coin slot 16 is closed by means of the closure bolt 56, so that no coin can be inserted into the dispenser when the same is empty. When the dispenser is empty an attendant unlocks the housing 14 and swings the same downwardly to permit a new pad of toilet seat covers or guards to be inserted in the magazine 12. When the housing is open, the coin chute closure mechanism is released by merely inserting a pencil or a pointed object through an aperture 64 in the partition plate 15 and into the aperture 60 of the ratchet wheel to push the latch pin 58 from the locking position shown in Figure 8 into its released position illustrated in Figure 7. As soon as the latch pin 58 75

is released, the control spring 61 swings the operating lever 55 from the locked dotted line position of Figure 6 back into its normal full line position. Attention is called to the fact that the circular graduated scale 50 on one surface of the ratchet wheel 49 is so arranged that the 100 mark is observable through the sight opening 52 when the magazine is full. It will be noted that with each revolution of the ratchet wheel 49 a complete pad of toilet seat guards or covers has been dispensed from the machine and the aperture 60 is brought into register permitting the latching pin 58 to be automatically projected into said aperture to move the coin opening closure bolt 56 into closed position.

The operation is as follows:

The improved dispenser with the adjustable supporting bracket is adapted to be mounted on a toilet bowl as illustrated in Figure 1 by means of the toilet cover hinge posts 2. The slotted feet 4 of the bracket are adapted to be positioned so that the hinge posts 2 project through either the front or the rear slot 5 to position the dispenser at a selected distance from the front of the toilet. The dispenser housing 14, by means of the vertical adjusting features of the bracket, may be raised or lowered with respect to the top of the toilet bowl by releasing the clamping bolts 7 and shifting the slotted bracket members 8 with respect to the guide members 6 forming an integral part of the base portions of the brackets.

With a full pad of toilet seat covers or guards mounted in the magazine 12 of the dispenser, and with the latching pin 58 in its released position as illustrated in Figure 7, a coin of a required denomination may be inserted into the coin receiving slot 16. Since the closure bolt 56 is in its retracted position the deposited coin is permitted to fall downwardly into the slot 18 between the coin pusher pin or stud 23 and the teeth 30 provided on one end of the operating bar 28. After the depositing of a coin an operator has merely to actuate the finger piece 21 thereby causing the control spring 41 to actuate the arm 42 and the main lever 43 to cause operation of the arms 45 and 46 whereby the bell crank 47 will be actuated to cause rocking of the upper cross rod 65 of the carriage. Rocking of the cross rod 65 serves to cause simultaneous upward swinging of the four hinge members 36 to cause the friction pads 38 to be projected through the plate openings 39 into contact with a folded portion of the outermost toilet seat guard in the dispenser magazine 12. With the operation of the finger piece 21, the pusher pin or stud 23 engages the periphery of the deposited coin and forces the same against the teeth 30 to slidably move the actuating bar 28 which in turn causes the traveling carriage to move downwardly from the position illustrated in Figure 5 to cause the advanced end of the engaged toilet seat guard to be projected downwardly out through the discharge opening in the bottom of the housing 14 against the guide apron 13.

With the advanced end of a toilet seat guard projected against the guide apron 13, the person operating the machine has merely to pull the guard out of the dispenser housing into a position to cover the top of the toilet seat 3. When the finger piece 21 is operated after the depositing of a coin in the coin slot 31, the slidable movement of the actuating bar 28 brings the end of the slot 66 thereof into engagement with the pin 67 carried by the upper end of the coin control

lever 55 thereby causing the coin control lever 55 to swing from the full line position of Figure 6 into the dotted line position to slide the closure bolt 56 inwardly in the coin slot 18 and at the same time cause the ratchet or pawl 51 to cause the ratchet wheel 49 to rotate 1/100th of a revolution. It will thus be noted that the aperture 60 in the ratchet wheel 49 is gradually advanced toward the position of the latching pin 58 each time a guard is discharged from the dispenser. When the last guard is dispensed the aperture 60 is brought into register with the locking pin 58 causing the control spring 59 to project the latching pin into the aperture 60 to lock the ratchet wheel against further rotation and at the same time swing the coin control lever 55 from the full line position of Figure 6 into the dotted line closure position to project the locking bolt 56 into position beneath the coin receiving slot 16 to close the machine against the further insertion of coins when the machine is empty.

With the improved counting or registering mechanism and the coin opening closure mechanism, it is impossible for anyone to insert a coin into the dispenser when the same is empty. The arrangement furthermore is an indication for an attendant to advise that the dispenser needs reloading.

It will of course be understood that various details of construction may be varied through a wide range without departing from the principles of this invention, and it is therefore not the purpose to limit the patent granted hereon otherwise than necessitated by the scope of the appended claims.

I claim as my invention:

1. The combination with a coin-controlled form dispenser having a coin receiving opening therein, of a coin control mechanism in the dispenser, a counting mechanism, means connecting the same for operation by the coin control mechanism each time a form is discharged from the dispenser, a closure member movable by said means across the coin receiving opening, and a control device connected with said counting mechanism for holding the closure member in a closing position across said opening to obviate the insertion of coins in the dispenser when the last form is discharged from the dispenser.

2. The combination with an article dispenser and the coin-control mechanism thereof, of a closure member, a counting mechanism, a slidable bar connecting the closure member and said counting mechanism for operation by the coin control mechanism, and a control means coacting with the counting mechanism when the last article is discharged from the dispenser to lock the counting mechanism and said closure member against further operation to obviate the insertion of a coin into the coin-control mechanism when the dispenser is empty.

3. In an article dispenser, the combination with an article dispensing mechanism, a coin-control means for operating the same to cause articles to be discharged from the dispenser one at a time each time a coin is inserted into the dispenser, a counting mechanism, means connecting the same to the dispensing mechanism to be operated by the coin control mechanism, a coin opening closure member operable by said means, and a latching device coacting with the counting mechanism to lock the same against operation when the dispenser is empty and furthermore hold the closure member positioned to prevent the insertion of coins into the coin control means.

4. In a coin-controlled article dispenser, a coin control means, a counting mechanism for registering the number of articles dispensed, a lever operated by the coin control means for actuating the counting mechanism, closure means connected to said lever and movable thereby into a position to prevent the insertion of coins into the dispenser, and a latching device carried by the lever for locking the lever, said closure means and the counting mechanism against operation when the last article is discharged from the dispenser to prevent the insertion of coins into the dispenser when the same is empty.
5. In a coin-controlled article dispenser, a coin control means, a ratchet wheel rotatably supported in the dispenser and having an opening
- therein, a spring controlled pivoted lever mounted to be operated by the coin control means, a pawl on said lever for operating the ratchet wheel each time an article is discharged from the dispenser, means on the ratchet wheel for indicating the number of articles dispensed, a closure member connected to said lever and movable thereby into a closing position to prevent the insertion of coins in the dispenser, and a spring controlled latching means carried by the lever to automatically project into the ratchet wheel opening when a predetermined number of articles have been dispensed to hold the closure member in a closing position.
